[57] CLAIM

The ornamental design for a personal digital assistant with a stylus compartment under a cover, as shown and described.

DESCRIPTION

FIG. 1 is a perspective view of a personal digital assistant shown in a cover-open position with a stylus shown stored in a compartment under the cover;

FIG. 2 is a front elevation view thereof shown with the stylus out of the compartment;

FIG. 3 is a perspective view thereof shown in a cover-closed position;

FIG. 4 is a left side elevation view thereof;

FIG. 5 is a right side elevation view thereof;

FIG. 6 is a front elevation view thereof;

FIG. 7 is a back elevation view thereof;

FIG. 8 is a top plan view thereof; and,

FIG. 9 is a bottom plan view thereof.
